UNITED STATES PATENT OFFICE

2,005,570

SHOULDER STRAP HOLDER

William J. Smith, Ridgefield Park, N. J.

Application November 25, 1933, Serial No. 699,663

14 Claims. (Cl. 24—73)

This invention relates to new and useful improvements in a shoulder strap holder.

This invention has for an object the construction of a shoulder strap holder which is characterized by a top cloth having an adhesive bottom side with a strap holding element removably mounted on the top side thereof and having a portion extending beneath said top side for being weakly adhesively held by said adhesive to be removable, and a bottom cloth as a pad beneath said top cloth at the area of said top cloth of the strap holding element

Still further it is also proposed to arrange the movable strips adhesively engaged to the bottom side of said top cloth and overlapping said bottom cloth.

Still further the invention proposes novel constructions and embodiments for the strap holding means which is associated as previously mentioned.

As another object of this invention it is proposed to construct an article as mentioned which is simple and durable and which may be manufactured and sold at a reasonable cost.

For further comprehension of the invention, and of the objects and advantages thereof, reference will be had to the following description and accompanying drawings, and to the appended claims to which the various novel features of the invention are more particularly set forth.

In the accompanying drawings forming a material part of this disclosure:—

Fig. 1 is a perspective view of a shoulder strap holder according to this invention.

Fig. 2 is a bottom elevational view of a strap holding element for use in conjunction with the device illustrated in Fig. 1.

Fig. 3 is an elevational view showing the application of a strap holding element of a slightly modified form to that illustrated in Fig. 2.

Fig. 4 is a bottom elevational view of another type of strap holding element.

Fig. 5 is an edge elevational view of Fig. 4.

Fig. 6 is a perspective view of another shoulder strap holder according to this invention.

Fig. 7 is a perspective view of another shoulder strap holder according to another embodiment of this invention.

Figs. 8—10 inclusive, are elevational views of various different shoulder strap holders according to various modifications of this invention.

Figs. 11—13 inclusive are elevational views of various shoulder strap holding elements for use, according to this invention.

Fig. 14 is a perspective view of another shoulder strap holder illustrating the invention.

Fig. 15 is an elevational view of a strap holding element for use in a shoulder strap holder according to this invention, and shown applied.

Figs. 16 and 17 are perspective views of shoulder strap holders according to further embodiments of this invention.

Fig. 18 is an elevational view of a strap holding element for use in a shoulder strap holder according to this invention.

Fig. 19 is a perspective view of several of the portions which compose a shoulder strap holder using the strap holding element illustrated in Fig. 18.

Fig. 20 shows the article in Fig. 19 with the bottom cloth or pad applied.

Fig. 21 is a front elevational view of another strap holding element for use according to this invention.

Fig. 22 illustrates an element slightly modified from that illustrated in Fig. 21 applied to a top cloth of a shoulder strap holder according to this invention.

Fig. 23 is a perspective view of another shoulder strap holder according to another embodiment of this invention.

Fig. 24 is a perspective rear view of Fig. 23.

Fig. 25 is a similar view to Fig. 24 showing a still further modification of the invention.

Fig. 26 is a perspective view of another shoulder strap holder according to this invention.

Fig. 27 is a perspective view of a garment strap holder according to a still further embodiment of this invention.

Fig. 28 is a perspective view of an extension strap holder for gripping the shoulder strap of an outer garment or dress.

Fig. 29 is similar to Fig. 28 but showing another attaching means of an extension shoulder strap holder.

The shoulder strap holder comprises a top cloth 10 having adhesive 11 on its bottom side and a central aperture 12 constituting one element for engaging and holding a strap holding element removably thereon. For example, in Fig. 2 a strap holding element has been illustrated comprising a strip of material 13 of a complete turn and a half with a button 14 upon the bottom side adapted to engage into the opening 12 for the connection of these parts. It should be noticed that the strap holding element therefore will have a portion extending beneath the top cloth 10 and being weakly adhesively held by the

5

55

adhesive 11 so as to be removable under slight force. A bottom cloth 15 acting as a pad is engaged beneath the top cloth 10 at the area of the strap holding element, that is the opening 12 and is attached in place by the adhesive 11 and simultaneously engages the portion of the strap holding element which extends beneath the top cloth, that is, the button 14 when the strap holding element is as illustrated in Fig. 2. Removable strips 16 are adhesively engaged upon the bottom side of the top cloth 10 and overlap each other, and further overlap the bottom cloth 15. The arrangement is such that the loose overlapping ends of the removable strip 16 may be pulled from place to expose the adhesive 11 so that the device may be attached upon one's shoulder by means of the adhesive.

In Fig. 3 a ribbon 17 is shown engaged between the coils of the strap holding element of a slightly modified form to that illustrated in Fig. 2. The advantage of the arrangement lies in the fact that the ribbon 17 may be easily engaged and removed from place without disturbing the strap holding element merely by engaging the ribbon first under one of the ends of the strip 13 and then under the other end. This arrangement will prevent the ribbon from being displaced while at the same time allows the ribbon to be loose. Of course, the ribbon 17 may constitute the shoulder strap of a garment, undergarment, or a number of shoulder straps of the same.

In Figs. 4 and 5 another embodiment of the strap holding element has been disclosed which may be used in conjunction with the holder illustrated in Fig. 1. This strap holding element comprises a frame made preferably by stamping sheet material. This frame comprises side walls 18 and end walls 19. A bar 20 extends across the centers of the side walls 18 one side 18 of the frame is open at the point 21 upon one side of the bar 20 and the other side 18 of the frame 20 is open at the point 22 of the other side of the bar. A button 23 is mounted upon the bottom side of the bar 20 for the purpose of engaging through the opening 12 for attaching the strap holding element upon the shoulder strap holder. A pair of longitudinal openings 19' are provided in end walls 19 for the purpose of attaching an extension holder which will be described hereinafter, for the purpose of holding additional shoulder straps of outer garment.

In Fig. 6 another embodiment of the invention has been disclosed in which a small snap fastener 24 is shown engaged through the opening 12. This snap fastener has a large base 25 which is adhesively held by the bottom cloth or pad 15. Instead of a button 23, a supplementary snap fastener may be provided on bar 20 to engage snap fastener member 24.

In Fig. 7 another modified arrangement has been disclosed in which the top cloth 10 is formed with a pair of spaced parallel straps 26, each formed by two parallel cuts so that the straps 26 really constitute loops. A strap holding element is shown engaged beneath the sides of the top cloth 10 and engaging up through the openings formed by the straps 26. This strap holding element comprises a metallic frame having sides 27 and top and bottom ends 28 and 29 respectively. The top end 28 is formed with a central cut 30 so that the opposite ends may be engaged respectively through the openings formed by the straps 26. A central bar 30' is arranged between the sides 27 and oppositely

directed prongs 31 project from the sides and constitute elements through which the ribbon may be engaged. The arrangement is similar to that illustrated in Fig. 3 wherein the ribbon may be engaged first beneath one prong from one direction and then beneath the other prong 31' of the other direction. A longitudinal slot 31' is provided in one of the prongs 31 for attaching an extension strap holding element, hereinafter described.

In Fig. 8 the shoulder strap holder is shown having the top cloth 10 formed with a plurality of strap portions 26. The strap holding element comprises a frame formed as clearly explained relative to Fig. 7, and corresponding parts being recognizable by the same reference numerals. The only distinction is in the arrangement of the bottom end 29 and of the frame which is also formed with an opening 30 so as to produce opposed ends. These opposed ends are adapted to engage the straps 26 as clearly illustrated in Fig. 8. The arrangement is such that the strap holding element is securely mounted and easily removable from the top of the top cloth 10. It should be understood that since the straps 26 are cut from the material of the top and bottom cloth the under side is also provided with adhesive 11 which necessarily engages the strap holding frame for weakly adhesively holding the frame so that the frame is removable when desired.

In Fig. 9 another modified arrangement of the device has been disclosed wherein the top cloth 10 is provided with upper and lower pairs of openings 33 adapted to receive the opposed ends of the upper and lower ends 28 and 29 respectively on the strap holding element. This strap holding element is also identical to that previously described and the same parts may be recognized by the same reference numerals.

In Fig. 10 another variation of the invention has been disclosed wherein the top cloth 10 is provided with strap portions 26' cut therefrom but arranged in horizontal instead of the vertical as the strap 26. With this device a strap holding element is supplied which comprises a frame 34 having ends and sides. A bar 35 connects the sides. Opposed prongs 36 project from the sides. Inward directed prongs 37 project from the ends and are adapted to be engaged beneath the straps 26' for holding the strap holding element upon the cloth. Longitudinal slots 36' are formed in prongs 36 for attachment of an extension strap holding element.

In Fig. 11 a detail has been illustrated of a strap holding element according to another form of this invention. This strap holding element comprises a substantially rectangular frame having sides 38, 39 and ends 40 and 41. Bars 42 and 43 extend between the sides 38 and 39. The sides 39 extend with an opening 44 communicating with an area between the bars 42 and 43. The side 38 is formed with an opening 45 to the outside of the bar 43. The end 40 is formed with an opening 46 to produce opposed ends for engaging the straps or openings upon the top of the ribbon cloth. The ribbon to be held by the device may be slipped in through the opening 44 and then through the opening 45 so as to be firmly and securely engaged upon the device. Slot 43' is formed in bar 43 for attaching an extension strap holder, such as shown in Fig. 28.

In Fig. 12 another strap holding element has been disclosed which comprises a frame of substantially elliptical shape with sides 48 and ends 75

49. The ends are formed with openings 50 to produce opposed portions for engaging the straps Figs. 7-9. A central bar 51 connects the sides or openings as previously described relative to 5
50 48. Opposed prongs 52 are provided for engaging and holding the shoulder strap, and are provided with longitudinal slots 53'.

10 In Fig. 13 another strap holding element has been illustrated which also comprises a frame of 10 rectangular shape having an engaging head 53 at one side for engaging suitable slots in top cloth 10. This frame also has a central cross bar 54 with a slot arrangement 54' and openings 15 55 upon the sides but on opposite sides of the cross bar 54. The operation of this device is readily understandable from previous descriptions of similar devices.

15 In Fig. 14 another variation of the invention has been disclosed in which the strap holding 20 element comprises a pair of clips 56 each identical and of substantially U-shape. These clips are formed with longitudinal slots 56' and are arranged on opposite edges of the top holding cloth 10 so that one of the arms may be engaged 25 beneath the adhesive material and the other arms extend upwards in opposite directions over the top of the top cloth 10, and thereafter covered with the bottom cloth 15 acting as a pad. Removable strips 16 are also provided for covering the adhesive.

30 In Fig. 15 another arrangement has been disclosed in which the top cloth 10 is provided with several loops 26 and a shoulder holding element is shown engaged thereon and comprises a frame 35 having a central bar 57 and opposed prongs 58 from opposite sides and on opposite sides of the central bar. This central bar is formed with an opening 59 to form opposed ends adapted to engage the loops 26. Snap fastener members 60 are 40 formed in prongs 58 for attaching suitable extension strap holders such as illustrated in Fig. 29 for the purpose of holding shoulder straps of outer garments.

45 In Fig. 16 another variation of the invention has been disclosed in which a ribbon 61 is slipped through the straps 26 of the top cloth 10 and bottom cloth 15. This ribbon 61 may be tied around the shoulder strap in a bow for the purpose of keeping the shoulder straps in place.

50 In Fig. 17 a small ribbon 62 is shown engaged to the straps 26 of the top cloth 10 adhesive 11 and bottom cloth 15. This small ribbon is provided with snap fastener elements 63 and 64 at the ends adapted to join the ends together for the 55 purpose of forming a loop which may hold the shoulder strap.

55 In Figs. 18-20 another arrangement has been disclosed wherein the strap holding element comprises a frame having sides 65 and ends 61. 60 Prongs 69 from opposite sides of the frame project in opposite directions are formed with attaching slots 68' and are adapted to hold a ribbon as described relative to Fig. 3. From the frame several gripping prongs 69 are formed from, and are 65 adapted to engage through the top cloth 10 and the adhesive 11 and be bent over as clearly illustrated in Fig. 19 for the purpose of attaching the strap holding element upon the top cloth. The bottom cloth 15 is then engaged upon the adhesive 11 and over the prongs 69 the device is completed with the removable straps now shown in this Fig. 70 1 previously shown and described, for example the parts 16 in Fig. 1.

75 In Figs. 21 and 22 another arrangement has been disclosed wherein the strap holding element

comprises a frame 70 with prongs 71 extended from opposite sides thereof and are formed with longitudinal slots 71' for the attachment of an extension strap holding element illustrated in Fig. 28. This frame is formed with projections 72 at the sides adapted to be bent around over the edges of the top cloth 10 for the purpose of attaching the strap holder element upon the top cloth. The bottom cloth 15 is then engaged upon the central portion of the top cloth 10 and covers 10 the edges 72.

15 In Figs. 23 and 24 the top cloth 10 and the bottom adhesive 11 are provided with a plurality of holes 73. These holes are cut through also a bottom cloth 74 for attaching the strap holding element. It is to be understood that any number of holes 73 may be used in any arrangement of locations and that the size and shape of these holes may be formed as desired.

20 In Fig. 25 the bottom cloth 75 is provided with an extension 76 which projects from the edge of the top cloth 10 and adhesive 11, to shield the skin from coming in contact with the shoulder strap element.

25 In Fig. 26 the strap holding element 77 is in the form of a resilient U-shape clip. One leg of this clip lies over the top cloth 10 and the other leg between the adhesive 11 and the bottom cloth 15. The clip is formed with an elongated slot 78 for the purpose of attaching an extension strap holder 30 shown in Fig. 28. The loose ends of the removable strips 16' are formed with bent edges 16a for interlocking each other.

35 In Fig. 27 a garment holder or buckle element 79 has been shown which is made of a more rigid construction to be able to support a heavier garment.

40 In Fig. 28 an extension member 80 has been shown for holding additional garment shoulder strap, and is provided with a suitable clip 81 to engage the elongated slots 19', 43', 53', 54' etc., in the various strap holding elements illustrated in Figs. 4, 7 and 11, respectively. The clip 81 is inserted in one of the said elongated openings by placing the extension member 80 in a transverse 45 position to the strap holding element and thereafter turning the extension member 80 into alignment with the said strap holding element. In this manner more than one strap holding element may be joined to grip the shoulder straps individually 50 or grouped as desired.

55 The extension member may be of a similar shape to any one of the shoulder strap elements except that it is provided with a clip 81. In the illustration, a pair of transverse prongs 82 has been shown for engaging the shoulder strap.

60 In Fig. 29 the extension member 83 is provided with projections 84 in which snap fastener members 85 are secured for attaching the extension member to complementary snap fastener members on the previously described strap holding elements in a manner shown in Fig. 15 in dot and dash lines.

65 While I have shown and described the preferred embodiment of my invention, it is to be understood that I do not limit myself to the precise construction herein disclosed and the right is reserved to all changes and modifications coming within the scope of the invention as defined in the appended claims.

70 Having thus described my invention, what I claim as new and desire to secure by United States Letters Patent is:

75 1. A shoulder strap holder, comprising a top cloth having adhesive on the bottom side, a

strap holding element mounted upon the top face of said top cloth and having a portion extending beneath said top cloth for being weakly adhesively held by said adhesive, a bottom cloth 5 as a pad beneath said top cloth and at the area immediately below said strap holding element and attached by said adhesive and simultaneously engaging the portion of said strap holding element beneath said top cloth, and removable straps adhesively engaged upon the bottom side of said top cloth and having overlapping ends extending over said bottom cloth.

2. A shoulder strap holder, comprising a top cloth having adhesive on the bottom side, a 15 strap holding element removably mounted upon the top face of said top cloth and having a portion extending beneath said top cloth for being weakly adhesively held by said adhesive so as to be removable therefrom, a bottom cloth as a 20 pad beneath said top cloth and at the area immediately below said strap holding element and attached by said adhesive and simultaneously engaging the portion of said strap holding element beneath said top cloth, and removable 25 straps adhesively engaged upon the bottom side of said top cloth and having overlapping ends extending over said bottom cloth, said top cloth being formed with several parallel cuts forming loops from said top cloth, and said holding strap element including opposed ends adapted to engage said loops.

3. A shoulder strap holder, comprising a top cloth having adhesive on the bottom side, a strap holding element removably mounted upon the top face of said top cloth and having a portion 35 extending beneath said top cloth for being weakly adhesively held by said adhesive so as to be removable therefrom, a bottom cloth as a pad beneath said top cloth and at the area immediately below said strap holding element 40 and attached by said adhesive and simultaneously engaging the portion of said strap holding element beneath said top cloth, and removable straps adhesively engaged upon the bottom side of said top cloth and having overlapping ends extending over said bottom cloth, said top cloth being provided with an opening, and said portion extending beneath said top cloth extending through said opening.

4. A garment holder comprising a top cloth 50 having adhesive on the bottom side, a strap holding element removably mounted upon the top face of said top cloth and having a portion extending beneath the said top cloth, a bottom cloth as a pad and at the area immediately below said strap holding element and attached by said adhesive and simultaneously engaging the portion of said strap holding element beneath said top cloth, and removable straps adhesively engaged upon the bottom side of said top cloth 55 and having overlapping ends extending over said bottom cloth.

5. A shoulder strap holder, comprising a top cloth having adhesive on the bottom side, a strap holding element removably mounted upon the top face of said top cloth and having a portion 65 extending beneath said top cloth for being weakly adhesively held by said adhesive so as to be removable therefrom, a bottom cloth as a pad beneath said top cloth and at the area immediately below said strap holding element and attached by said adhesive and simultaneously engaging the portion of said strap holding element beneath said top cloth, and removable straps adhesively engaged upon the bottom side of said top cloth 70 and having overlapping ends extending over said bottom cloth.

extending over said bottom cloth, a snap fastener extending through said top cloth and having its base beneath the top cloth and said bottom cloth and constituting an element for attaching said strap holding element.

6. A shoulder strap holder, comprising a top cloth having adhesive on the bottom side, a strap holding element removably mounted upon the top face of said top cloth and having a portion extending beneath said top cloth for being weakly adhesively held by said adhesive so as to be removable therefrom, a bottom cloth as a pad beneath said top cloth and at the area immediately below said strap holding element and attached by said adhesive and simultaneously engaging the portion of said strap holding element beneath said top cloth, and removable straps adhesively engaged upon the bottom side of said top cloth and having overlapping ends extending over said bottom cloth, said top cloth being formed with several parallel cuts forming loops from said top cloth, and said holding strap element including opposed ends adapted to engage said loops.

7. A shoulder strap holder, comprising a top cloth having adhesive on the bottom side, a strap holding element removably mounted upon the top face of said top cloth and having a portion extending beneath said top cloth for being weakly adhesively held by said adhesive so as to be removable therefrom, a bottom cloth as a pad beneath said top cloth and at the area immediately below said strap holding element and attached by said adhesive and simultaneously engaging the portion of said strap holding element beneath said top cloth, and removable straps adhesively engaged upon the bottom side of said top cloth and having overlapping ends extending over said bottom cloth, said top cloth being formed with several parallel cuts forming loops from said top cloth, and said holding strap element including opposed ends adapted to engage said loops, portions of said opposed ends being disposed upon the adhesive sides of said loops.

8. A shoulder strap holder, comprising a top cloth having adhesive on the bottom side, a strap holding element removably mounted upon the top face of said top cloth and having a portion extending beneath said top cloth for being weakly adhesively held by said adhesive so as to be removable therefrom, a bottom cloth as a pad beneath said top cloth and at the area immediately below said strap holding element and attached by said adhesive and simultaneously engaging the portion of said strap holding element beneath said top cloth, and removable straps adhesively engaged upon the bottom side of said top cloth and having overlapping ends extending over said bottom cloth, said top cloth being formed with apertures, and said strap holding element having opposed ends engaging into said apertures and constituting the portions beneath said top cloth.

9. A shoulder strap holder, comprising a top cloth having adhesive on the bottom side, a strap holding element removably mounted upon the top face of said top cloth and having a portion extending beneath said top cloth for being weakly adhesively held by said adhesive so as to be removable therefrom, a bottom cloth as a pad beneath said top cloth and at the area immediately below said strap holding element and attached by said adhesive and simultaneously engaging the portion of said strap holding element beneath said top cloth, and removable straps adhesively engaged upon the bottom side of said top cloth and having overlapping ends extending over said bottom cloth.

bottom cloth, said top cloth having cuts forming several transverse loops, and said holding elements having elements extending beneath said loops in constituting the holding of the strap 5 holding element in place.

10. A shoulder strap holder, comprising a top cloth having adhesive on the bottom side, a strap holding element removably mounted upon the top face of said top cloth and having a portion 10 extending beneath said top cloth for being weakly adhesively held by said adhesive so as to be removable therefrom, a bottom cloth as a pad beneath said top cloth and at the area immediately below said strap holding element and attached by 15 said adhesive and simultaneously engaging the portion of said strap holding element beneath said top cloth, and removable straps adhesively engaged upon the bottom side of said top cloth and having overlapping ends extending over said 20 bottom cloth, said strap holding element comprising a pair of loop members having one of their ends engaged beneath the edge of the top cloth and having their other ends extending in opposite directions over said top cloth.

25. 11. A shoulder strap holder, comprising a top cloth having adhesive on the bottom side, a strap holding element removably mounted upon the top face of said top cloth and having a portion extending beneath said top cloth for being weakly 30 adhesively held by said adhesive so as to be removable therefrom, a bottom cloth as a pad beneath said top cloth and at the area immediately below said strap holding element and attached by said adhesive and simultaneously engaging the portion of said strap holding element beneath said top cloth, and removable straps adhesively engaged upon the bottom side of said top cloth and having overlapping ends extending over said bottom cloth, snap fastener elements being arranged 35 40 upon said strap holding element to act in conjunction therewith.

45. 12. A shoulder strap holder, comprising a top cloth having adhesive on the bottom side, a strap holding element removably mounted upon the top face of said top cloth and having a portion extending beneath said top cloth for being weakly adhesively held by said adhesive so as to be removable therefrom, a bottom cloth as a pad beneath said top cloth and at the area immediately 45

below said strap holding element and attached by said adhesive and simultaneously engaging the portion of said strap holding element beneath said top cloth, and removable straps adhesively engaged upon the bottom side of said top cloth and having overlapping ends extending over said bottom cloth, said strap holding element comprising a ribbon engaged through loops formed by parallel cuts in said top cloth.

13. A shoulder strap holder, comprising a top 10 cloth having adhesive on the bottom side, a strap holding element removably mounted upon the top face of said top cloth and having a portion extending beneath said top cloth for being weakly adhesively held by said adhesive so as to be removable therefrom, a bottom cloth as a pad beneath said top cloth and at the area immediately 15 below said strap holding element and attached by said adhesive and simultaneously engaging the portion of said strap holding element beneath said top cloth, and removable straps adhesively engaged upon the bottom side of said top cloth and having overlapping ends extending over said bottom cloth, said strap holding element comprising a ribbon engaged through loops formed by 20 parallel cuts in said top cloth, means upon the ends of said ribbon for joining the ends to form a loop to hold the shoulder strap.

14. A shoulder strap holder, comprising a top cloth having adhesive on the bottom side, a strap 30 holding element removably mounted upon the top face of said top cloth and having a portion extending beneath said top cloth for being weakly adhesively held by said adhesive so as to be removable therefrom, a bottom cloth as a pad beneath said top cloth and at the area immediately 35 below said strap holding element and attached by said adhesive and simultaneously engaging the portion of said strap holding element beneath said top cloth, and removable straps adhesively 40 engaged upon the bottom side of said top cloth and having overlapping ends extending over said bottom cloth, said strap holding element comprising a frame with opposed prongs for holding said prongs projecting from said frame engaging 45 through said top cloth to the under side, and said bottom cloth covering the ends of said prongs.

WILLIAM J. SMITH.
